FEED TUBE SUPPORT

Alfred F. Jelinek and Walter E. Gross, Cleveland,
Ohio, assignors to The Cleveland Automatic
Machine Company, Cleveland, Ohio, a corpo-
ration of Ohio

Application July 20, 1940, Serial No. 346,597

5 Claims. (Cl. 29—62)

This invention relates broadly to automatic multi-spindle screw machines and more specifically to improvements in feed tube supporting mechanisms therefor.

One of the objects of the invention is to provide a feed tube support which is adapted for ready assembly within the machine and constructed to afford accessibility thereto in replacing the stock feed fingers.

Another object of the invention is to provide a feed tube supporting ring which is organized to rotate within the spindle housing contemporaneous the index movement of the spindle in order to align the feed tubes with the mechanism for advancing the bar stock towards the collets.

Another object of the invention is to provide a feed tube sleeve adapted for engagement with a mechanism to effect the rapid forward translation of the stock feed tube and a decelerated return movement thereof.

Another object of the present invention is to provide a plurality of stock feed tubes adapted to be engaged in sequence by a spring actuated arm for advancing the stock feed tube and bar stock therein towards the spindle collet.

Other objects and advantages more or less ancillary to the foregoing and the manner in which all the various objects are realized will appear in the following description, which considered in connection with the accompanying drawings, sets forth the preferred embodiment of the invention.

Referring to the drawings wherein the preferred embodiment of the invention is illustrated;

Fig. 1 is a front elevational view of an automatic multi-spindle screw machine having a section of the spindle housing casing removed therefrom and showing the stock feed tube supporting ring and its appurtenances in section;

Fig. 2 is an elevation of the fragmentary portion of the machine as viewed from the spindle housing end thereof;

Fig. 3 is an enlarged sectional view of the stock feed tube assembly, the section being taken on a plane indicated by line 3—3 of Fig. 2;

Fig. 4 is a longitudinal sectional view of one of the stock feed tubes and the supporting members associated therewith; and

Fig. 5 is a sectional view through the mechanism for effecting the translation of the stock feed tube towards a collet tube, the section being taken on a plane indicated by line 5—5 of Fig. 2.

Referring to Fig. 1, the multi-spindle screw machine illustrated herein embodies generally a base 11, a tool slide housing 12 and a spindle housing 13. Upon the top of the housing 12

there is a motor 14 having a sprocket upon the outer end of its armature shaft which is coupled with gearing, not shown, for driving the spindles and actuating mechanisms within the housings 12 and 13.

The stock feed tube assembly is supported by a plurality of rollers 15 (Figs. 2 and 3) mounted in brackets 16 secured upon webs formed on the walls of the spindle housing 13. The inner end 10 of the spindle bearing cage 17 is provided with a spider 18 rigidly affixed thereto and formed with a guide rod 19 which is piloted in the stock feed tube supporting ring 20 carried by the rollers 15. The stock feed tubes 21 have one of the ends 15 thereof mounted in collet tubes 22 while the opposite ends are supported in sleeves 30, which are suitably keyed for longitudinal movement within the ring 20. The end portions of the stock feed tubes are slotted in the customary manner 20 to form resilient fingers 23 for frictional engagement with the bar stock extended therethrough.

The periphery of the outer end of the stock feed tubes is reinforced with a ferrule 24 having a conical head 25 on the end thereof, which is seated within a tapered bore formed in the enlarged end portion of a sleeve 26 telescopically engaged with the ferrule 24. The periphery of the enlarged end portion of the sleeve 26 is threaded for the reception of a nut 27 formed 25 with an inturned flange for engagement with the shouldered end of the conical head 25 to facilitate the securement of the sleeve in fixed relation with the ferrule. The end of the ferrule is threaded to receive a nut 28 for locking the nut 27 in adjusted position upon the sleeve. The end 30 portions of the sleeve 26 are provided with anti-friction bearings 29 upon the outer race of which there is mounted a sleeve 30 having a feather key 31 therein to facilitate the reciprocative movement thereof within the ring 20. The inner and outer races of the bearings 29 are locked respectively against longitudinal movement so that the sleeve 26 and in turn the stock feed tube may be reciprocated by movement of the sleeve 30. The inner end of the sleeve 30 is formed with a pair of spaced flanges defining a groove or guide-way 32, which is adapted to receive a segmental arm 33 organized to effect the retraction of the stock feed tube in timed relation with the collet actuating mechanism.

The segmental arm 33 is affixed upon a slide 34 which is guided on a rod 35 supported by a transverse wall in the housing 13 and a bracket 36 mounted upon a web within the end portion 55 of the spindle housing. The slide is formed with

a depending arm 37 having a roller 38 in the end thereof, which is engageable with a rotatable cam 39 mounted in the spindle housing. The slide 34 is further provided with a laterally extended arm 40 (Figs. 2 and 5) which is bored to receive a tube 41 welded or otherwise affixed therein. The inner end of the tube is closed by a bushing 42 constituting a seat for a spring 43 mounted within the tube 41. The spring is guided by a rod 44 which is supported in a bracket 45 mounted on a web within the spindle housing 13. The adjustable collar 46 mounted on the guide rod 44 retains the spring 43 in compression with the bushing 42 for normally urging the slide and stock feed tube inwardly.

As will be seen in Figs. 2 and 5, the slide 34 is constructed with a second laterally extended arm 48 having a yoke 49 in the end thereof engaged with a stationary rod 50 to restrain the sleeve from rotative movement about the rod 35. The sleeves are held in aligned relation during the index period of the machine by a split ring 51 supported within the spindle housing and adapted for engagement with the grooved portions of the sleeves as they are successively discharged from the segmental arm 33.

In operation as the spindle bearing cage and in turn the supporting ring 20 is indexed to the station in which the stock feed operation occurs, the grooved portions of the sleeves 30 are brought in order into engagement with the segmental arm 33, the cam 39 at this instant in the operative cycle being timed so that the roller 38 moves beyond the point A on the cam plate, thereby allowing the spring 43 to impart a rapid forward movement to the slide 34 and stock feed tube 21 for advancing the stock gripped by the spring fingers through the collet. A stop 52 secured to the rod 35 so limits the movement of the stock feed tube and slide as to bring the roller 38 into engagement with the cam plate at the point B.

As the roller ascends the inclined surface of the cam the feed tube fingers will slide over the bar stock until the roller reaches the dwell C formed on the cam plate, at which time the segmental arm is in aligned relation with the track formed by the split ring 51 so that the grooved portion of the sleeve 30 may be transferred thereto and the sleeve in the following indexed position may be engaged by the segment 33.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

We claim:

1. A screw machine embodying a spindle housing, an indexable spindle cage therein, a plurality of rotatable spindles in said cage, a ring mounted in said housing rotatively connected with said cage, a plurality of sleeves having grooves in the ends thereof slidably mounted in said ring, stock feed tubes secured in said sleeves and slidably in said spindles, a rod mounted in said spindle housing and means on said rod for successively en-

gaging the grooves in said sleeves to transmit movement to the stock feed tubes therein.

2. A screw machine embodying a spindle housing, an indexable spindle cage therein, rotatable spindles in said cage, a spider affixed to said spindle cage, a shaft connected thereto, a ring mounted on said shaft, rollers mounted in said spindle housing supporting said ring, sleeves having grooves therein slidably mounted in said ring, stock feed tubes affixed in said sleeves and slidably in said spindles, a rotatable cam in said spindle housing, a rod secured in the spindle housing, a slide mounted thereon, a segmental arm on said slide, a second arm depending from said slide and engaging said cam, said segmental arm being coordinated for sequential operation with grooves in the respective sleeves to effect the movement of the stock feed tubes contemporaneous the rotation of the cam.

3. A screw machine embodying a housing having a plurality of rotatable spindles therein, an indexable supporting member therefor, a roller supported ring mounted in said housing and affixed to said member, sleeves having grooves formed therein slidably mounted in said ring, stock feed tubes secured in said sleeves and slidably within said spindles, a rod supported in said spindle housing, a slide thereon, and means on said slide engaging said grooves in said sleeves upon the indexing of the spindle supporting member and means coordinated with said slide to advance the stock feed tubes subsequent the indexing operation.

4. A screw machine embodying a housing having a rotatably indexable spindle cage therein, a plurality of spindles in said cage, a ring mounted in said housing rotatively connected with said spindle cage, sleeves slidably mounted in said ring and having grooves formed in the ends thereof, stock feed tubes secured in said sleeves and slidably in said spindles, a rod supported in said housing, a slide thereon, a cam in said housing, a segmental arm extending from said slide for successively engaging the grooves in said sleeves upon the indexed movement of the spindle cage, a compression spring associated with said slide to effect the forward movement of the sleeves subsequent the indexed movement of the spindle cage, and means on said slide coacting with said cam to move said sleeves to their initial positions.

5. A multi-spindle screw machine embodying a housing having a plurality of rotatable spindles therein, an indexable spindle supporting cage, a spider affixed to said spindle cage, a shaft extending therefrom, a ring secured to said shaft, rollers mounted in said housing supporting said ring, sleeves having grooves therein slidably mounted in said ring, stock feed tubes affixed in said sleeves and slidably mounted in the spindles, a rotating cam in said housing, a rod in said housing, a slide thereon, a split ring in said housing, constituting a track engaged with the grooves in the sleeves, a segmental arm on said slide completing the annulus of said split ring within a portion of the indexed cycle of the machine, said cam and slide advancing one of the sleeves out of the path of the annular track.
